UNITED STATES PATENT OFFICE.

JOHN W. HICKS, OF MADISON, WISCONSIN.

DESIGN FOR A CANDELABRUM.

Application filed August 30, 1924. Serial No. 10,631. Term of patent 14 years.

To all whom it may concern:

Be it known that I, JOHN W. HICKS, a citizen of the United States, residing at Madison, in the county of Dane and State of Wisconsin, have invented a new, original, and ornamental Design for a Candelabrum, of which the following is a specification, reference being had to the accompanying drawing, forming part thereof.

In the drawing the figure shows a perspective view of my design for a candelabrum.

I claim:

The ornamental design for a candelabrum, as shown.

JOHN W. HICKS.
